UNITED STATES PATENT OFFICE.

JOHN P. CONLIN, OF BROOKLYN, NEW YORK.

CHECK VALVE.

Application filed April 25, 1919. Serial No. 292,701.

To all whom it may concern:

Be it known that I, JOHN P. CONLIN, a citizen of the United States, and a resident of Brooklyn, county of Kings, city and State of New York, have invented new and useful Improvements in Check Valves, of which the following is a specification.

This invention relates to check valves, particularly of the character used in air or gas compressors, vacuum pumps and analogous apparatus.

The objects of the invention are to provide a valve which is especially adapted for operation at high speeds: which allows a large port opening with a small movement of the valve element which will wear for a long period, and which does not require lubrication.

A further object of the invention is to provide a valve of this character which is self-grinding, whereby the valve element continues to make a tight closure against its seat until so worn as to no longer have the structural strength required to hold pressures against it.

A further object of the invention is to provide a valve of this character which embodies but few parts and which is designed to permit ready replacement of the movable valve elements without special tools or grinding of the parts together.

Another advantage of the valve consists in the provision of a novel form of spring and valve element so designed that should either part break, the broken part cannot escape from the valve and drop into the cylinder. Also, the valve is of symmetrical exterior construction so that any valve may be used as either a suction or discharge valve by simply reversing the valve itself.

Further advantages of my improved valve will appear from the following specification wherein I have described a preferred embodiment thereof which is especially adapted for use in ammonia compressors for ice-making machines, but which may of course be used wherever a check valve is necessary.

In the drawings, Fig. 1 shows my improved valve in cross section with the parts assembled ready for insertion in the machine in which it is to be used;

Fig. 2 is a plan view looking in the direction of the arrow, Fig. 1, showing the several parts of the valve broken away;

Figs. 3 and 4 are respectively plan views

of the two main parts of the valve showing the faces opposite to those shown in Fig. 2; and

Fig. 5 shows in cross section an ammonia compressor of typical design equipped with my improved valves.

Referring to the drawings, 1 indicates one half of the valve which may be termed the body thereof which, as here shown, comprises a plate of steel, cast iron or other suitable metal having a central hole 2 for the clamping bolt 3 by means of which the valve parts are secured together.

The inner face of the plate 1 is provided with a recess or countersink 4 which is surrounded by an annular flange 5 forming one edge of the valve seat for the inner valve ring 6. The valve ring 6 is preferably formed of medium hard steel and consists merely of a flat ring of a width sufficient to cover the inner annular valve port 7 with its inner edge seated against the flange 5 and its outer edge against a similar flange 8 surrounding the annular port.

The valve may consist of a single ring but I prefer to employ two or more rings as shown, the outer ring being concentric with the inner ring and covering a similar annular port 10 concentric with the port 7. The face of the valve body 1 is turned down around the outer valve seat as shown at 11 and the face of the disk is also provided with a groove 12 between the flange 8 and the inner valve seat of the outer ring whereby the edges of the rings project beyond the edges of the flanges forming their valve seats for the purpose which will be presently described.

The two annular ports 7 and 10 are bridged at intervals by webs 13^a of ample width to maintain the disk against distortion under the strains to which it is to be subjected, and the valve ports are preferably flared toward the outer face of the disk to permit an easy flow of the fluid.

The valve rings are held against their seats by springs 13 which are preferably of the type shown, that is, the springs are coiled in a spiral after the manner of a watch spring with the inner or small end thrust axially out of the plane of the larger end. I preferably employ three such springs for each ring, the springs being set in recesses 14 bored in the face of the valve cap 15 which is also formed of a disk of metal of the same diameter as the valve body 1.

The holes in the valve cap are of the same diameter as the large end of the valve springs, whereby the valve springs fit snugly in the holes and are maintained in place 5 without interfering with their action.

Between the recesses in which the springs are located the cap is provided with a series of arcuate ports 16 for the discharge of fluid drawn through the valve, the ports 10 being as large as consistent with the desired rigidity of the structure.

To allow free movement of the valves the face of the valve cap adjacent the rings is formed with an annular recess of sufficient 15 depth to allow the desired opening of the valves which need not, in a valve such as shown, be of a greater extent than indicated in the drawing. At the outer edge of the annular recess there is a flange 17, and at 20 the center of the disk there is a hub 18, the faces of the flange 17 and hub 18 being machined or ground to fit against the machined or ground surfaces of the part 1 to thereby form an air-tight closure between the two 25 parts without packing when they are clamped together by means of the center bolt 3.

The same valve structure is designed to be used as either a suction or discharge 30 valve by simply reversing the bolt 3 so as to have the nut on the outside, to which end both the valve cap and valve body are turned down around their outer edges to provide similar shoulders 19 so as to fit the 35 same cylinder opening in either position. In Figs. 1 and 2 of the drawings I have shown the valve arranged for use as a discharge valve, that is, the head of the bolt is on the side of the body 1 of the valve.

40 This feature of the valve is shown in Fig. 5 which shows the cylinder 20 of a typical compressor with suction valves 21 on its upper side and discharge valves 22 on the lower side, the suction valves having the 45 caps 15 turned toward the interior of the cylinder while the discharge valves have the valve bodies 1 on the inside.

The parts may be bolted together in suitable manner, so long as the bolt does not 50 project beyond the valve at one end. In the arrangement shown, the bolt 3 which has no head is first screwed into the part which is to be on the inside (the body 1 in Fig. 1) until its end projects into the conical recess 55 24 on its outer face, and the end riveted down into the recess as shown. After the springs and valve rings are arranged in place the cap 15 will be assembled in place on the bolt and the locking nut put on the 60 outer end of the bolt. With this construction there is little likelihood of the bolt

loosening and dropping into the path of the piston.

In this connection it will also be noted that the springs 13 are of larger diameter than 65 the width of the annular ports in the valve body so that should the ring break or be worn through out of the springs, the spring will not pass through the port into the cylinder. 70

It will be noted that the valve rings have a certain limited play on their seats, due to the lateral flexibility of the springs, and this lateral movement permits the valve rings to creep on their seats, due to the 75 vibration of the parts when the compressor is in operation, with the result that the valve is virtually self-grinding, the marginal edges of the rings maintaining a true surface and a gas-tight joint against the valve 80 seats until worn out.

Another important feature of my improved valve is the arrangement of the three annular ports in the valve cap in staggered 85 relation to the two ports in the valve body, 90 whereby the ribs or webs between the valve ports and the cap lie opposite the centers of of the rings so that when the valve opens the rings are drawn back against these ribs which uniformly reinforce them and prevent warping, even with very thin rings. Due to the valve construction a small movement of the rings gives a full port opening. The small movement of the ring permits 95 very rapid operation practically without noise and without excessive compression of the springs.

In the foregoing specification I have described the preferred embodiment of my invention in detail, but it is of course to be 100 understood that the invention is not limited to such details except in so far as recited in the appended claims.

I claim:

A valve of the class described comprising 105 two parts, shoulders on said parts for retaining the valve in the cylinder opening with either of said parts facing the cylinder, a plurality of concentric annular ports in said parts, a plurality of separate, flat 110 concentric rings positioned to cover said ports, the edges of the ports being raised to form seats for said rings, springs for holding said rings against said ports, said rings being permitted a limited amount 115 of lateral movement, whereby said rings will creep on their seats and grind the contacting surfaces to form a gas-tight joint.

Signed at New York, in the county of New York, and State of New York, this 4 day of 120 April, 1919.

JOHN P. CONLIN.
